UNITED STATES PATENT OFFICE.

THOMAS BRADY, OF EAST ORANGE, NEW JERSEY, ASSIGNOR, BY MESNE ASSIGNMENTS, TO OTIS ELEVATOR COMPANY, OF NEW YORK, N. Y., A CORPORATION OF NEW JERSEY.

DOOR CLOSURE.

Original application filed February 15, 1923, Serial No. 619,231. Divided and this application filed October 10, 1925. Serial No. 61,643.

This invention relates to door closures and, particularly, to closures such as are used for elevator hatchway doors.

This application is a division of application Serial No. 619,231, filed February 15, 1923.

It is common practice at the present time to manufacture door closures of different sizes to fit the various sizes of doors. This practice involves expense since it necessitates carrying in stock several sizes of links and operating parts. Furthermore, it often happens that on installation further fitting and adjusting is necessary and this still further increases the cost of the installation.

This invention has for its object to provide a standard closure device so constructed and arranged that it can be readily adjusted and effectively used with a plurality of different sizes of door installations.

Another object of the invention is to provide a door closure so constructed as to be capable of adjustment in a manner to properly align the operating links so as to reduce to a minimum the friction between the coacting parts.

Another object of the invention is to provide a device of the character described that is simple in construction, efficient in operation and inexpensive to manufacture.

Further objects of the invention will appear from the following specification taken in connection with the drawings, which form a part of this application, and in which—

Fig. 1 is an elevational view of a door installation showing operating and checking mechanism constructed in accordance with the invention.

Fig. 2 is a transverse sectional view taken substantially on line 2—2 of Fig. 1.

Fig. 3 is a sectional elevation similar to Fig. 2, but showing the door section in open position.

Fig. 4 is a detail elevational view on an enlarged scale showing the pivotal connection between one of the operating links and one of the door sections.

Fig. 5 is an elevational view taken at right angles to Fig. 4.

Fig. 6 is an elevational view similar to Fig. 4, but showing the pivotal connection between adjacent links.

Fig. 7 is a transverse sectional elevation taken substantially on line 7—7 of Fig. 6.

Fig. 8 is an elevational view of the handle. 55

Fig. 9 is an end view taken at right angles to Fig. 8.

Fig. 10 is a detail sectional elevation showing the roller mounting for the door sections.

Fig. 11 is a detail sectional elevation 60 showing the guiding means for the lower ends of the door sections.

Fig. 12 is an elevational view on an enlarged scale showing the construction of the adjustable joints between the sections of the 65 end link which is pivoted to the fixed abutment, and

Fig. 13 is a top plan view of the construction shown in Fig. 12.

The invention briefly described consists of 70 means for operating a plurality of sliding door sections and this means comprises links pivotally connected to the door sections and to each other, one of the end links being pivoted on a fixed pivot. In order to adapt 75 the device for use in connection with the different sizes of door sections and door installations, means is provided for adjustably connecting the links to the door sections and for adjustably connecting the links to each other. The end link which is connected to a fixed pivot is made sectional and the sections are adjustably connected so that the links may be properly aligned with reference 80 to the doors, as, in order to avoid undue friction, the links should be disposed in planes parallel to the planes of the door sections. 85

In the embodiment of the invention shown the door comprises a stationary section 20 90 and slidable sections 21 and 22, these two latter sections being adapted to move into overlapping position with the stationary section 20 as shown in Fig. 3.

The door sections may be mounted in any desired manner and in the particular form of the invention illustrated each of the sections 21 and 22 is provided with rollers 23 mounted on a rail 24 disposed above the hatchway opening. The door sections are 100 also guided by means of downwardly extending webs 25 (see Fig. 11) which are disposed in slots 26 formed in a plate 27 mounted at the bottom of the hatchway opening. 105

Operating means for the slidable door sections comprises a plurality of links A, B and C. The link A is adjustably mount-

ed in a clamp 30 which is pivoted at 31 on a plate 32 secured to the door section 22. The construction of the clamp 30 is illustrated in detail in Figs. 4 and 5 and from these figures it will be seen that the clamp comprises parallel plates 33 and 34 adapted to receive between them the end portion of the link A and when this link has been properly adjusted in the clamp, the clamp is tightened by means of screws 35. A lug 36 extends upwardly from the clamp and is pivoted as before stated at 31 to the plate 32.

The link A is pivotally connected to the link B through an adjustable clamp 40 illustrated in detail in Figs. 6 and 7. This clamp comprises parallel plates 41 and 42 adapted to receive between them one end portion of the link B and screws 43 secure this link portion in its adjusted position. The clamp 40 is connected by a pivot pin 44 to the link A.

The link B is pivotally connected intermediate its ends to the door section 21 in the following manner. A bracket 50 is preferably adjustably secured to one side edge of the section 21, this bracket having a plate 51 formed thereon. The link B is adjustably connected to the plate 51 by means of a clamp 52 exactly similar in construction to the clamp 30 already described and, therefore, the details of this clamp will not be specifically explained. The link B is pivotally connected to the free end of the link C by means of a clamp 55 exactly similar in construction to the clamp 40 already described.

The link C comprises a plurality of sections which are designated for convenience as C', C² and C³. The section C³ is pivotally mounted on a horizontal pivot 60 formed in a bracket 61. The bracket 61 is secured to a vertically disposed plate or strip 62 secured at 63 to one side wall of the elevator hatchway.

Since dimensions vary and the construction of the hatchway is not uniform, it is desirable to provide means for adjustably connecting the sections C', C² and C³ of the end link C to each other for the purpose of properly alining the links A, B and C as these links should be disposed in planes parallel to the planes of the door sections in order to operate effectively and with a minimum amount of friction. These adjustable connections are particularly illustrated in Figs. 12 and 13 and may be described as follows. The section C' of the end link has secured to one end an adjustable clamp 65 similar in construction to the clamps already described. The clamp 65, however, has formed thereon an ear 66 and the section C² has formed on one end parallel ears 67 so spaced apart as to receive the ear 66 as shown in Figs. 1 and 12. Each of these ears has an opening formed therethrough and

the opening is preferably star-shaped or provided with radial notches 68. These openings are adapted to register when the ears 66 and 67 are placed in overlapping relation and the clamp 65 is connected to the end of the section C² by means of a bolt 70. This bolt is also star-shaped in section and properly dimensioned to fit within the openings in the ears 66 and 67. The bolt 70 has reduced threaded extensions 71 and 72 and on these extensions are mounted nuts 73. In order to adjust the sections C' and C², the bolt 70, which connects these parts, is removed and the link C is properly alined with reference to the links A and B and with reference to the planes of the door sections. The section C² is then angled to the desired position and the bolt 70 is inserted and thereafter the nuts are tightened securely clamping these parts in adjusted position. A similar joint is formed between the sections C² and C³, this joint being indicated by the reference character 75 and as this joint is exactly similar to that already described, no further explanation thereof is deemed necessary.

From the foregoing description it will be seen that a wide range of adjustment between the sections C', C² and C³ can be obtained and that these sections can be properly adjusted to aline the link C with the remaining links of the door sections.

A handle 80 is adjustably secured to the operative links and in the particular embodiment of the invention shown, this handle is connected to an end of the link B disposed beyond the pivotal connection between the links A and B. The construction of this handle is particularly illustrated in Figs. 8 and 9 wherein it will be seen that the handle comprises parallel plates 81 and 82 which receive between them the end of the link B. Screws 83 are provided for clamping these plates to the link. A hand grip or extension 84 is formed on the plate 81. It will, of course, be understood that if the operator desires the handle can be secured to the links in another position as, for instance, to the link B on the opposite side of the pivotal connection between the links A and B. The position of the handle will be determined by the size and reach of the operator.

The actuating and cushioning mechanism for the door closure need not be described in detail since this mechanism forms the subject matter of application, Serial No. 619,231, of which this application is a division. Briefly, the mechanism comprises a rod 90 adjustably connected by a socket 91 threaded to the upper end of the rod to an extension 92 formed on the section C³ of the link C. The socket 91 is pivoted at 93 to the extension 92.

The rod 90 extends downwardly into a cyl-

inder 94, the lower end of which is closed by a plug 95 and this plug is pivoted at 96 on a bracket 97 secured to the strip 62.

The door closure mechanism is installed 5 and operated in the following manner. The door sections are first moved to the closed position shown in Fig. 1. The links A, B and C are then pivotally connected to each other and pivoted to the door sections in 10 such a position that they will be properly aligned with reference to each other and to the door sections. The sections of the link C, namely, C¹, C² and C³, are then relatively adjusted with reference to each other and 15 pivotally connected at 60 to the bracket 61 in such a manner that the links A, B and C will be disposed parallel to each other and to the door sections. The operating and cushioning means is then secured to the 20 section C³ of the link C at the pivot point 93 and the opposite end of this means is pivoted at 96 to the bracket 97. Before the ends of the actuating and cushioning means are connected to the extension 92 and bracket 25 97 respectively, the socket 91 will be adjusted to properly position the rod 90. When these parts have been adjusted in the manner described and the handle 80 has been mounted in the desired position on the links, the 30 mechanism may be operated as follows.

Assuming that the doors are in closed position, the operator will pull downwardly on the handle 80 thereby causing the door sections 21 and 22 to slide to the position shown 35 in Fig. 3 and the links A, B and C will take the positions shown by the dotted lines in Fig. 1. As the link C is swung upwardly, the extension 92 on the section C³ of the link will move from the position shown in full 40 lines in Fig. 1 to the dotted line position or approximately at right angles to its initial position. This will cause the rod 90 to be pulled out of the cylinder 94, thus bringing 45 into operation spring return mechanism and cushioning means described and claimed in the copending application above referred to.

From the foregoing description it will be seen that simple, practical and effective means has been designed for accomplishing the objects of the invention. By means of the various adjustments a standard outfit can be manufactured and applied to doors of various sizes and dimensions. Furthermore, the adjustments described permit the 55 accurate mounting of the device when installed and facilitate the proper alinement and thereby eliminate all unnecessary friction.

Although the door illustrated in the drawings has two sliding sections, it will be understood that, if desired, a single sliding section or more than two sliding sections may be used, without change in the operating mechanism, except as to the number of links 60 used. Although one specific embodiment of

the invention has been particularly shown and described, it will be understood that the invention is capable of modification and that changes in the arrangement and in the construction of the various cooperating parts 70 may be made without departing from the spirit or scope of the invention as expressed in the following claims.

What I claim is:

1. Door closure mechanism for sectional 75 doors comprising a series of links pivoted respectively to the door sections and to each other and connected at one end to a fixed pivot, the link connected to the fixed pivot comprising a plurality of relatively adjustable sections whereby the links can be adjusted toward and from the door and properly aligned with reference to the door sections.

2. Door closure mechanism for sectional 80 doors comprising a series of links pivoted respectively to the door sections and to each other and connected at one end to a fixed pivot, the pivotal connections between the links and doors comprising clamps adjust- 90 able on said links.

3. Door closure mechanism for sectional 95 doors comprising a series of links pivoted respectively to the door sections and to each other and connected at one end to a fixed pivot, the pivotal connections between the links and doors and between the respective links being adjustable.

4. Door closure mechanism comprising a 100 plurality of door sections, slid able one over the other, a link adjustably pivoted to each door section, a link pivoted on a fixed pivot, and adjustable pivotal connections between the links pivoted to the door sections and between one of said links and the link piv- 105

oted on the fixed pivot.

5. Door closure mechanism for slid able 110 sectional doors comprising links connected to the door sections and to a link pivoted on a fixed pivot, said last named link comprising a plurality of sections relatively adjustable about axes substantially parallel to the planes of the door sections.

6. Door closure mechanism for doors having a slid able section comprising a link piv- 115 otted to said section and a link pivoted to said first link and on a fixed pivot, said second link comprising a plurality of sections relatively adjustable with reference to each other and laterally with reference to 120 the planes of the door sections.

7. Door closure mechanism for doors having a slid able section comprising a link piv- 125 otted to said section and a link pivoted to said first link and on a fixed pivot, said sec- ond link comprising a plurality of sections relatively adjustable about axes substantially parallel to the planes of the slid able sections with reference to each other.

8. Door closure mechanism comprising a 130

slidable door section and a link adjustably pivoted to said section, and a second link adjustably pivoted to said first link on an axis perpendicular to the plane of the door section and to a fixed pivot.

9. Door closure mechanism comprising a slidable door section and a link adjustably pivoted to said section, and a second link

adjustably pivoted to said first link on an axis perpendicular to the plane of the door section and to a fixed pivot, said second link comprising a plurality of relatively adjustable sections.

In witness whereof, I have hereunto set my hand this 5th day of October, 1925.

THOMAS BRADY.
